United States Patent

Des. 241,467
Patented Sept. 14, 1976

241,467

THERAPEUTIC LAMP

Petrus Jacobus Johanna Nagelkerke, Drachten, Netherlands, assignor to U.S. Philips Corporation, New York, N.Y.

Filed Sept. 11, 1974, Ser. No. 504,910

Claims priority, application Netherlands Mar. 18, 1974

Term of patent 14 years

Int. Cl. D24—01

U.S. Cl. D48—20 H

FIG. 1 is a perspective view of a therapeutic lamp showing my new design;

FIG. 2 is a front elevational view;

FIG. 3 is a rear elevational view;

FIG. 4 is a right side elevational view;

FIG. 5 is a left side elevational view;

FIG. 6 is a top plan view; and

FIG. 7 is a bottom plan view.

I claim:

The ornamental design for a therapeutic lamp, as shown and described.
